UNITED STATES PATENT OFFICE.

JOSEPH A. NEAL, OF MOBILE, ALABAMA, ASSIGNEE OF ONE-HALF TO STOVER LUMBER COMPANY, OF MOBILE, ALABAMA, A CORPORATION OF ALABAMA.

RESAWING MACHINE.

Application filed March 5, 1925. Serial No. 18,291.

This invention relates to sawing machines, and more particularly to machines for resawing lumber as it leaves the planing mill.

One object of my present invention is to improve the construction and increase the efficiency and durability of resawing machines such as shown and described in my Patent No. 1,340,286, dated May 18, 1920, for a twin circular resawing machine.

Another object of the invention is to provide a resawing machine having twin circular saws mounted on a rocking or tilting frame extending across a main supporting frame and provided with means for adjusting and securing the tilting frame and saws in different positions at an angle to the main frame, so as to adapt the saws to cut the stock on a bevel, or at any desired angle to a horizontal plane, together with means for changing the angular position of the saws at will independently of the simultaneous adjustment provided by the tilting frame.

Another object is to provide a tilting saw-carrying frame mounted on a main supporting frame with means for adjusting and securing the tilting frame and saws thereon in different positions at an angle to a horizontal plane, so as to adapt the saws to cut the stock on a bevel, without changing the position of the saws relative to the frame on which they are mounted, together with means for changing the angular position of the saws each independently of the other and independently of the adjustment provided by the tilting frame, and also means for adjusting the saws vertically and laterally and securing them at different heights and at different distances apart for cutting material of different thicknesses and widths.

A further object is to provide a machine of the character referred to with simple and efficient means for adjusting the saws laterally and at an angle to a horizontal plane, and holding them rigidly in different positions and to prevent or reduce to a minimum the danger of accidental displacement or shifting of the position of either saw when once adjusted and secured in the desired position.

Other objects are to provide in a resawing machine a rigid and durable frame structure of both the main supporting frame and the tilting frame mounted thereon, together with improved laterally and angularly adjustable mandrel-supporting frames with

associated shaft bearings and vertically adjustable shafts carrying circular saws, as will hereinafter more fully appear.

The invention will first be hereinafter more particularly described, with reference 60 to the accompanying drawings, which are to be taken as a part of this specification, and then pointed out in the claims at the end of the description.

In said drawings, Fig. 1 is a plan view of 65 a twin circular resawing machine embodying my invention;

Fig. 2 is a rear elevation of the same partly broken away;

Fig. 3 is a vertical transverse sectional 70 elevation, on a slightly enlarged scale over that shown in Figs. 1 and 2, the section being taken on the line 3-3 of Fig. 1, looking in the direction of the arrows, and the auxiliary frame in adjusted position being 75 indicated in dotted lines;

Fig. 4 is a vertical longitudinal sectional 80 elevation taken on a line about midway of the length of the machine frame on the line 4-4 of Fig. 1, substantially at right angles 85 to the section shown in Fig. 3;

Fig. 5 is a side elevation of the machine;

Fig. 6 is a detail sectional plan view of the lower frame bar of the tilting saw-carrying 85 frame and its connections with the main supporting frame;

Fig. 7 is a detail vertical sectional elevation of one of the mandrel-supporting frames and vertical shaft bearings associated therewith, showing the connections between 90 the same and the tilting frame; and

Fig. 8 is a side elevation, partly in section, of said mandrel-supporting frame and shaft bearings and connections between the same and the tilting frame. 95

Referring to said drawings, in which the same reference letters are used to denote corresponding parts in different views, the letter A denotes metal plates forming the front and rear sides of the main supporting frame, and B the sides or ends thereof, which are rectangular in form, one being substantially a counterpart of the other, and said sides and ends are secured together in box-like form, at the four corners thereof. The front and rear side plates A have inwardly turned upper and lower horizontal marginal flanges a and a¹ connecting vertical end flanges a², and depending triangular strengthening end portions a³ co-extensive 100

with said end flanges; the latter being suitably apertured to receive fastening bolts inserted through said apertures and registering apertures in opposite ends of said 5 sides or ends B, as indicated in dotted lines in Figs. 1 and 2, whereby the four sides are rigidly secured together. Said sides or ends B have outwardly extending horizontal top and bottom flanges b and b¹ and intermediate spaced flanges b², and also vertical spaced flanges b³, at each end, and intermediate vertical spaced flanges b⁴, connecting the top and bottom and intermediate horizontal flanges. The top flanges b terminate 10 at their junction with the intermediate vertical flanges b⁴ and the metal plate above the intermediate horizontal flanges and between the intermediate vertical flanges is cut away so as to provide vertical open-ended gaps 15 or guide-ways on opposite sides of the main frame for the heads C on opposite ends of an auxiliary tilting frame on which are mounted circular saws D. The tilting frame is mounted intermediate its ends on 20 a transverse beam or bar E, which has reduced and rounded ends e fitted in bearings therefor in the front and rear sides of the main supporting frame so as to permit a rotary to and fro movement of said beam 25 in its bearings and adapt it to serve as a rock-shaft on which the auxiliary frame is rockably supported; said bearings being formed integrally with said front and rear side plates in the form of hollow projections or bosses about midway thereof, as 30 shown in Figs. 2 and 4 of the drawings. Said auxiliary frame has upper frame members F and F¹, one of which is arranged slightly ahead of the other and which are 35 preferably round and have reduced end portions inserted in holes or sockets provided therefor in the rock shaft E, at one end, and in the heads C at the other end, or at opposite ends of the tilting frame; the free 40 ends of said reduced end portions of said frame members being threaded and having nuts screwed thereon for securing them in place, as shown in Fig. 3. The rock-shaft or cross-bar E is preferably of metal and 45 formed or provided with a depending member E¹ about midway thereof and with diagonal downwardly and inwardly inclined members or braces E², thus forming a triangular frame structure or support for the 50 tilting frame. The intermediate upright member E¹ and the diagonal members E² are united at their lower ends and merge in or are jointed to a substantially square and flat-bottomed foot-plate E³, which is 55 bolted or otherwise rigidly secured to a similarly shaped seat g about midway of a lower horizontal frame bar G of the tilting frame. Said bar G has bifurcated or forked ends which fit astride upwardly and 60 outwardly inclined members h of guide- 65 brackets H, secured upon opposite sides of the main frame; set screws h¹ being inserted in the bifurcated ends of the bar G for securing the ends thereof to the bracket members h, so as to firmly hold the lower part 70 of the tilting frame in a fixed position either horizontally or at any desired angle to the main frame. The heads C to which the outer ends of the horizontal frame members or guide-bars F and F¹ of the tilting frame 75 are secured are preferably formed integrally with depending, inwardly inclined legs I, of channel iron or U-shaped form in cross-section, which connect said heads and the upper frame members of the tilting frame with the outer end-portions of the lower horizontal frame bar G, the latter being of channel iron form in cross-section or having grooves in its upper surface on 80 opposite sides of its center to receive and 85 guide means whereby the lower ends of the mandrel-frames may be adjusted laterally and firmly secured in different positions. About midway of the bar G there is an offset portion with a flat top forming the seat 90 g, Fig. 6, which is suitably apertured at the four corners thereof for attachment to the foot-plate E³, by bolts and nuts. This construction places one half of the bar G 95 slightly in advance of the other half and parallel with the upper guide and frame member of the tilting frame on the same side of the machine, while the other half is arranged parallel with the other upper frame member on the opposite side of the machine, thus adapting said upper members F and F¹ and lower members G to support 100 and hold the mandrel frames in proper alignment with provision for lateral adjustment thereof along the bar G and guide-bars F and F¹, for adjusting and securing the saws at different distances apart and at different angles, to adapt the saws to cut 105 the stock on a bevel. For the purpose of adjusting and securing 110 the tilting frame in different positions, to change the angle of the saws, the heads C are each formed or provided with a laterally projecting boss e having an oblong open-ended socket therein to receive a ball 115 or spherical head on the upper end of an adjusting screw K, thus forming a universal joint: the screw being passed through a threaded aperture in a lug K¹ projecting from one side B of the main frame, 120 so that the adjacent end of the tilting frame may be raised or lowered by turning the screw to the right or left. The lower end of the screw may be of polygonal form for applying thereto a wrench or other tool to 125 serve as a handle for turning it. To compensate for the change of position of the boss having the socket in which the spherical head of the screw works when the adjacent end of the tilting frame is raised or lowered, 130

and to adapt the screw to maintain a true vertical position without binding in different positions of the tilting frame, the screw has a reduced portion or neck which slidably 5 engages an oblong slot in the bottom of the socket so that relative movement of the head of the screw inwardly or outwardly along the length of the socket is permitted as the tilting frame is raised or lowered. In 10 each of the heads C, between the bosses c thereon and the holes through which the reduced ends of the tilting frame members or guide-bars F and F¹ are inserted there are formed two parallel holes in one of which is 15 inserted the plain outer end of an adjusting screw or rod L, one at each side of the machine frame, and in the other a revolute eccentric locking bar or rod M. Endwise movement of the adjusting screw and locking bar is prevented by means of nuts or 20 collars fixed thereon on opposite sides of the head C, as shown in Fig. 3, and the outer ends thereof are of polygonal form for the attachment of a suitable tool for imparting 25 rotary movement thereto. The inner portion of the rod M is flattened on one side, facing a reduced end-portion of a set screw n⁴ (Figs. 7 and 8), the body of which is threaded and screwed into a socket in the 30 sliding head N with its reduced end-portion crossing the opening in which the rod M is fitted, and its lower side is arranged slightly below the top of said opening, so that when 35 the rod is turned its round surface will press tightly against said end-portion of said screw and lock the sliding head in a fixed position; but when the flattened side of the rod faces said end portion of the set screw there will be sufficient clearance between the 40 two parts to release or unlock the sliding head and permit it to be moved along the guide bar on which it is mounted by rotating the adjusting screw L, thereby moving the saw toward or from the center of the 45 machine, according to the direction in which the adjusting screw is turned. The exposed end of the set screw n⁴ is polygonal in form for applying thereto a suitable tool for turning it. The threaded part of the 50 adjusting screw passes loosely through a hole in a sliding head or block N on the upper end of an upright mandrel-supporting frame O, and through a threaded hole in a nut n which is housed within a recess in said 55 head or block and causes it to move therewith along the guide bar F or F¹ when the adjusting screw is turned. Mandrel-supporting frames O are arranged one at each side of the triangular frame member or rock- 60 shaft E on which the tilting frame is mounted, and have associated therewith vertical shaft bearings and means for adjusting and securing them rigidly in place at different distances apart, and also means for adjust- 65 ing the saws vertically and at an angle to a horizontal plane independently of the simultaneous angular adjustment provided by the auxiliary tilting frame. The upper end of the mandrel frame is substantially of L-shaped form or provided with an offset extension o, so as to provide a recess to receive the sliding head or block N, which fits snugly in said recess and is seated on the upper end of said support, at the base of said recess. The sliding head or block has a depending portion n¹ with oblong slots therein and which overlaps the upper end of the support O and is secured thereto by a set screw or screws n² inserted in said slots while 70 its upper end is secured to the extension o of the mandrel frame by a pivot bolt or screw n³ passing through a hole in the block and screwed into a threaded aperture in a boss or protuberance o¹ on the upper end of said extension, so as to permit a slight 75 swinging movement of the mandrel frame on said pivot bolt as a center, when its lower end is adjusted as hereinafter described and to permit such movement the lower part of the sliding head has a slightly rounded or 80 convex surface in contact with the surface of the mandrel frame on which it is seated at the base of the offset extension o, as shown in Fig. 3; the head itself being held against 85 similar movement by the guide bar passing 90 therethrough. A set screw n⁵ is screwed into a threaded aperture in the sliding head or block N, below the pivot bolt n³, so as to bear upon the guide bar and hold the head 95 in a fixed position. For the purpose of adjusting and securing the lower end of the mandrel frame in different positions corresponding with the lateral adjustment of its upper end, or to angularly adjust the 100 mandrel to change the angle of the saw mounted thereon in the plane in which its carrying frame is rockably adjustable, its lower end is recessed to receive a laterally 105 slideable and forwardly and rearwardly adjustable locking device P (Figs. 3 and 7) 110 having a depending lug p working in a groove in the lower auxiliary frame bar G; the head portion of said locking device being of tubular form and interiorly threaded and fitted upon an adjusting screw p¹ which has 115 an inner reduced end revolvably fitted in a socket in the lower end-portion of the mandrel frame; the outer end of the screw being of polygonal form for applying thereto a 120 suitable tool for turning it so as to cause the lug p to frictionally engage and bear tightly against a wall of the groove in which it slides and hold the lower end of the mandrel frame in a fixed position. Sufficient 125 clearance is provided between the base of the locking device P and the surface of the auxiliary frame bar G to permit the desired adjustment, to which end said base is also rounded, as shown in Fig. 3. The screw p¹ is formed or provided with a collar 130

p^2 near its outer end which fits in a recess in the outer side of a cover plate p^3 secured on the lower end of the mandrel frame by means of set screws p^4 passing through an outer plate p^5 placed between the heads of the screws and said cover plate and through apertures in the cover plate and screwed into sockets or holes in the mandrel frame. The outer plate p^5 overlies the recess in which the collar p^2 is fitted and the outer end-portion of the screw passes through a hole in said outer plate and has a lock nut p^6 thereon, bearing against the outer side of said outer plate so as to prevent endwise movement thereof when the screw is turned to move the locking device into or out of binding contact with the outer or inner wall of the groove in the frame bar G. The mandrel-supporting frames have associated therewith suitable bearings for vertical shafts on which the saws D are mounted, and for this purpose the lower parts thereof and also their upward extensions o are each formed or provided with a semi-circular recess and laterally projecting apertured lugs o^3 for attaching thereto a similarly recessed cover plate the upper one of which is denoted by the letter Q and the lower one by the letter q^1 . These cover plates have laterally projecting apertured lugs thereon through which set screws are inserted and screwed into sockets or holes in the lugs o^3 on the mandrel frame for securing the two parts together. The cover plates are hollow, thus providing each with an oil chamber having a vertical oblong slot at its upper end in communication with the bearing surfaces formed by the confronting semi-circular recesses in the mandrel frame and attached cover plates, and each cover plate is provided with an inlet pipe q through which oil or other lubricant is introduced for lubricating the shaft bearings. Sleeves R and R^1 are placed around the vertical shaft within the openings formed by the semi-circular recesses of the upper and lower bearing members and oblong slots are formed therein in communication with the oil chambers in the cover plates through the oblong slots in the upper ends of the latter. Anti-friction bearings are provided for the lower ends of the vertical shafts, comprising a cup-like housing S secured on the underside of the lower end of each mandrel frame by means of belts or screws passing through apertures in an annular flange s at the upper end of the housing and screwed into sockets or holes in the mandrel frame; said housings containing preferably well-known types of annular end-thrust ball bearings placed between a bearing ring s^1 and a plate or disk s^2 within the housing; the vertical shaft having a reduced end portion which fits in the ring s^1 , thus centering the shaft thereon. An adjusting bolt S^1 is screwed into a threaded

aperture in the bottom or lower end of the housing and bears against the plate or disks s^2 , so as to provide for slight vertical adjustment of the shaft by turning said bolt, which has a lock nut s^3 thereon adapted to bear against the lower end of the housing and prevent the bolt from turning without first loosening the nut.

The transverse beam E, as shown in Fig. 4, has machine-faced portions E⁴ on opposite sides thereof formed with oblong slots therein to receive fastening bolts for attaching thereto separating devices such as are shown in Fig. 1 and which are fully illustrated and described in my co-pending application, Serial No. 13,293, filed March 5, 1925, and are not claimed herein, so that further illustration or description thereof herein is thought to be unnecessary; one of said devices being indicated in dotted lines in Fig. 4 and the other on the rear side being removed.

Having thus described my invention, what I claim as new and desire to secure by Letters Patent of the United States is:

1. A resawing machine comprising a main supporting frame having vertical guideways on opposite sides thereof, an auxiliary frame supported intermediate its ends on a rock-shaft journaled in bearings carried by said main frame and having its ends slidably fitted in said guideways; said auxiliary frame extending across said main frame substantially at right angles to said rock-shaft and having twin circular saws mounted thereon, one at each side of said rock-shaft, and means for tilting said auxiliary frame and securing it in different positions at an angle to a horizontal plane, so as to adapt the saws to cut the stock on a bevel.

2. A resawing machine comprising a main supporting frame having vertical guideways on opposite sides thereof, an auxiliary frame supported intermediate its ends on a rock-shaft journaled in bearings on the front and rear sides of said main frame and having its ends slidably fitted in said guideways; said auxiliary frame having laterally adjustable twin circular saws mounted thereon, one at each side of said rock-shaft, and means for tilting said auxiliary frame and securing it in different positions at an angle to a horizontal plane, so as to adapt the saws to cut the stock on a bevel.

3. A renewing machine comprising a main supporting frame having vertical guideways on opposite sides thereof and shaft bearings on its front and rear sides, an auxiliary frame supported about midway its length on a rock-shaft journaled in said bearings and having its ends slidably fitted in said guideways, mandrel-supporting frames mounted on said auxiliary frame, one at each side of said rock-shaft and carrying twin circular saws, one arranged slightly in advance of

the other, means for tilting and securing said auxiliary frame in different positions so as to adapt the saws to cut the stock on a bevel, and means for adjusting said mandrel-frames laterally and securing them in different positions, for varying the distance between the saws.

4. A resawing machine comprising a main supporting frame having vertical guideways on opposite sides thereof and shaft bearings on its front and rear sides, an auxiliary frame rockably supported about midway its length on a rock-shaft journaled in said bearings and having its ends slidably fitted in said guideways, mandrel-supporting frames mounted on said auxiliary frame, one at each side of said rock-shaft, twin circular saws carried by said mandrel-frames, one arranged slightly in advance of the other, means for tilting and securing said auxiliary frame in different positions so as to adapt the saws to cut the stock on a bevel, means for angularly adjusting the saw mandrels in the plane in which their carrying frame is rockably adjustable, and means for adjusting said mandrel-frames laterally and securing them in different positions, for varying the distance between the saws.

5. A resawing machine comprising a main supporting frame having vertical guideways on opposite sides thereof and shaft bearings on its front and rear sides, an auxiliary frame supported about midway its length on a rock-shaft journaled in said bearings and having its ends slidably fitted in said guideways, mandrel-supporting frames mounted on said auxiliary frame, one at each side of said rock-shaft, vertically adjustable twin circular saws carried by said mandrel-frames, one arranged slightly in advance of the other, means for adjusting said mandrel-frames laterally and securing them in different positions, for varying the distance between the saws, and means for tilting and locking said auxiliary frame in different positions so as to adapt the saws to cut the stock on a bevel.

6. A resawing machine comprising a main supporting frame having vertical guideways on opposite sides thereof and shaft bearings on its front and rear sides, an auxiliary frame rockably supported about midway its length on a rock-shaft journaled in said bearings and having its ends slidably fitted in said guideways, laterally adjustable mandrel-supporting frames mounted on said auxiliary frame, one at each side of said rock-shaft, vertically adjustable twin circular saws carried by said mandrel-frames, one arranged slightly in advance of the other, means for tilting and securing said auxiliary frame in different inclined positions so as to adapt the saws to cut the stock on a bevel, and means for angularly adjusting the saw mandrels in the plane in which

their carrying frame is rockably adjustable and securing them in different inclined positions.

7. A resawing machine comprising a main supporting frame having vertical guideways on opposite sides thereof, an auxiliary frame rockably supported intermediate its ends on a rock-shaft journaled in bearings on the front and rear sides of said main frame and having its ends slidably fitted in said guideways; said auxiliary frame having upper and lower guide-bars to which are slidably secured the upper and lower ends of laterally and angularly adjustable mandrel-supporting frames carrying twin circular saws, one at each side of said rock-shaft, and means for tilting said auxiliary frame and securing it in different positions at an angle to a horizontal plane, so as to adapt the saws to cut the stock on a bevel.

8. A resawing machine comprising a main supporting frame having vertical guideways on opposite sides thereof, an auxiliary frame supported intermediate its ends on a rock-shaft journaled in bearings on the front and rear sides of said main frame and having its ends slidably fitted in said guideways; said auxiliary frame having upper and lower guide bars to which are slidably secured the upper and lower ends of laterally adjustable mandrel-supporting frames carrying twin circular saws, one at each side of said rock-shaft, and means at opposite ends of said auxiliary frame for tilting and securing it in different positions at an angle to a horizontal plane, so as to adapt the saws to cut the stock on a bevel, together with adjustable means for securing opposite ends of said lower guide-bar to opposite sides of said main frame.

9. A resawing machine comprising a main supporting frame having vertical guideways on opposite sides thereof, an auxiliary frame rockably supported intermediate its ends on a rock-shaft journaled in bearings on the front and rear sides of said main frame and having its ends slidably fitted in said guideways; said auxiliary frame having upper and lower guide-bars carrying laterally adjustable mandrel-supporting frames and twin circular saws mounted on mandrels journaled in vertical shaft bearings on said mandrel frames, one at each side of said rock-shaft, means for tilting said auxiliary frame and securing it in different positions at an angle to a horizontal plane, so as to adapt the saws to cut the stock on a bevel, and means for angularly adjusting and securing the saw mandrels in the plane in which their carrying frame is rockably adjustable.

10. The combination, in a resawing machine, of a main supporting frame, an auxiliary frame rockably supported intermediate its ends on said main frame and carrying

mandrel-supporting frames each having a circular saw mounted thereon; said saws being mounted on vertical shafts journaled in upper and lower bearings carried by said 5 mandrel-frames, means for tilting said auxiliary frame and securing it in different positions at an angle to a horizontal plane, so as to adapt the saws to cut the stock on a bevel, and means for angularly adjusting the 10 saw mandrels in the plane in which their carrying frame is rockably adjustable.

11. The combination, in a resawing machine, of a main supporting frame having vertical guideways on opposite sides thereof 15 and oppositely disposed shaft bearings on its other two sides, an auxiliary frame rockably supported about midway its length on a rockable beam having round ends journaled in said bearings; said auxiliary frame carrying mandrel-supporting frames each having a circular saw mounted thereon and having its ends slidably fitted in said guideways, and means for tilting and securing said auxiliary frame in different positions to adapt 20 the saws to cut the stock on a bevel; said means comprising a longitudinally vertically adjustable screw having a slidable ball-and-socket-joint connection with one end of 25 said auxiliary frame to adapt the screw to said auxiliary frame to maintain a perpendicular position relative to the tilting frame when the latter is adjusted and secured at different angles to said main frame.

12. A resawing machine comprising a 30 main supporting frame having vertical guideways on opposite sides thereof and oppositely disposed shaft bearings on its other two sides, an auxiliary frame supported about midway its length on a rock-shaft 35 journalized in said bearings and having its ends slidably fitted in said guideways, and means for tilting and securing said auxiliary frame in different positions to change the angle of the saws relatively to its supporting 40 frame; said tilting and securing means comprising a hollow boss or socket on the auxiliary frame having an oblong slot therein and a longitudinally vertically adjustable screw supported on said main frame and having a 45 ball on its upper end connecting a neck portion thereof with the body of the screw; said ball being arranged within said socket, and said neck slidably engaging said slot; said auxiliary frame carrying mandrel-supporting 50 frames having twin circular saws mounted thereon.

13. The combination, in a resawing machine, of a main supporting frame, an auxiliary frame rockingly supported on said 55 main frame, said auxiliary frame carrying mandrel-supporting frames each provided with shaft bearings, a vertical shaft journaled in said bearings and having a circular saw mounted thereon, said mandrel frame having a pivotal connection at its upper end 60

with said auxiliary frame and having means for adjusting and securing its lower end at different points along the length of a lower frame bar of said auxiliary frame, whereby the mandrel-frame may be adjusted and secured in a slanting position to change the angle of the saw, and means for tilting said auxiliary frame and securing it in different inclined positions to change the angle of the saws. 75

14. In a resawing machine, a mandrel-supporting frame carrying upper and lower shaft bearings, a vertical shaft journaled in said bearings and having a circular saw mounted thereon, said mandrel-frame having a pivotal connection at its upper end with a frame structure rockably supported intermediate its ends on a main supporting frame and having a lower frame bar adjustably secured to said main frame and means for 80 adjusting and securing the lower end of said mandrel-frame at different points along the length of said lower frame bar of said frame structure, whereby the mandrel-frame may be adjusted in the plane in which its carrying frame is rockably adjustable and secured in a slanting position to change the angle of the saw. 85

15. In a resawing machine, a mandrel-supporting frame carrying upper and lower shaft bearings, a vertical shaft journaled in said bearings and having a circular saw mounted thereon, said mandrel-frame having a pivotal connection at its upper end with a frame structure rockably supported intermediate its ends on a main supporting frame and having a lower frame bar adjustably secured to said main frame and means for adjusting and securing the lower end of said mandrel-frame at different points along the length of said lower frame bar of said frame structure, whereby the mandrel-frame may be adjusted in the plane in which its carrying frame is rockably adjustable and secured in a slanting position to change the angle of the saw. 90

16. In a resawing machine, the combination with a main supporting frame, of an auxiliary frame rockingly supported intermediate its ends on said main frame, said auxiliary frame having upper and lower guide bars arranged in substantially the same vertical plane at each side of the longitudinal center of said main frame, the lower guide bar having its ends angularly adjustably secured to said main frame and mandrel-supporting frames angularly adjustably secured to said upper and lower guide bars for changing the angle of the saws mounted thereon and carrying upper and lower shaft bearings and twin circular saws mounted on vertical shafts journaled in said bearings. 115 120 125 130

and means for tilting said auxiliary frame and securing it in different positions to change the angle of the saws and adapt them to cut the stock on a bevel.

- 6 17. In a resawing machine, laterally adjustable mandrel-supporting frames slidably mounted on an upper frame bar of a frame structure extending across a main supporting frame, and means for adjusting and securing
10 said mandrel-frames at different distances apart; said means comprising an adjusting screw and a locking rod passing through parallel openings in a head portion or block carried by each mandrel-frame, said screw
15 also passing through a nut non-rotatably confined in a recess in said block, whereby the

block is caused to travel with the nut when the screw is turned, and a set screw inserted in a hole in said block and having a plain inner end portion which extends across the 20 opening through which said rod passes; said rod being flattened on one side so as to provide a clearance between it and the set screw when said flat side is turned toward the screw, thus releasing the sliding head or 25 block, the inner portion of said set screw being adapted to impinge upon said rod when facing the round surface thereof and hold the block in a fixed position.

In testimony whereof I affix my signature.

JOSEPH A. NEAL.
